UNITED STATES PATENT OFFICE

2,610,238

ELECTRICAL AUTOMOBILE SAFETY DEVICE

Rudolf Joksch, Vienna, Austria, assignor of one-half to Fritz Gruenberg, Vienna, Austria

Application March 11, 1949, Serial No. 80,997

4 Claims. (Cl. 177—314)

1

This invention relates to an electrical safety device for motor vehicles driven by an internal combustion engine, and more particularly to a combined electrical arrangement of a starting and a coil or battery ignition system.

The main purpose of this invention is to provide a safety device of the above kind wherein an alarm device is operated in response of various manipulations of an unauthorized person, in order to indicate such manipulations to other persons near the car and thus to prevent or at least to impede a theft of the car.

A further important object of this present invention is to provide a safety device of the above kind, wherein the alarm signal sounds so as to call the driver's attention to the fact that he is leaving the car with the engine standing still, without having turned off the usual ignition switch, in order to protect the battery from being exhausted. In such a manner, moreover, the breaker contact points of the ignition circuit are protected from being damaged due to an arc-flame with the engine standing still. The alarm signal sounds also when the driver is starting the engine and has forgotten to previously switch on the ignition switch so that the battery is protected from exhaustion also due to such useless attempts of starting.

Another object of this invention is to provide a safety device of the above kind, wherein an alarm signal is actuated as soon as an unauthorized person attempts to short-circuit the ignition switch being in its off-position, with one of the doors of the car not being properly closed. The signal sounds, moreover, when the doors of the car are closed, when the ignition circuit has been completed in such an unauthorized manner and when any attempt of starting is made. In a preferred form of the invention, a simple device is provided whereby upon such unauthorized starting action the ignition current is automatically weakened so that no sparks are obtained at the spark plugs of the engine.

A still further object of this invention is to provide a safety device of the above kind wherein an alarm signal is actuated as soon as with the engine standing still an unauthorized person operates the clutch lever or pedal to separate the engine from the gear set, with the intention to tow the automobile away. It is to be noted that towing of the car is rendered impossible or at least remarkably impeded with the gear set connected to the engine.

Another object of the invention is to provide a safety device of the above kind wherein the alarm

2

device is automatically rendered inactive, when the engine is normally started and the generator driven by the same, shows a relatively low number of revolutions, or when the engine is unintentionally stopped in the street traffic of a town, whereby an undesired and disturbing action of the alarm device is avoided.

A still other object of this invention is to provide a safety device of the above kind wherein the alarm signal sounds if the engine is being started with one or more of the doors of the vehicle being not properly closed, in order to remove the danger of the vehicle beginning to move with one or more of its doors open.

15 A further object of this invention is to provide a safety device of the above kind, which is simple and reliable and can be made at low costs, the operation of such a device being completely automatic and additional, hand-operated switches or similar members are not required. In a preferred form of the invention, the usual horn is used as an alarm device so that additional alarm devices, such as electrical buzzers or the like, are dispensed with, the arrangement being such that the normal actuation of the horn as a warning signal is not interfered with.

Further objects and advantages of the present invention will be apparent from the following description.

30 In the accompanying drawing a wiring diagram of one embodiment of this invention is illustrated by way of example. For the sake of clearness, several parts are shown in different scales and the elements not necessary for understanding the invention, are omitted.

The battery 2 is connected to the ground 1 and through the starter switch 4 to the starter motor 5. The ignition switch 6 is constructed so that it interconnects in its on-position a pair of contacts 7, and in its off-position another pair of contacts 8. The battery 2 is connected by a line 9 to the contacts 7, to a charging switch 10 and further with one brush of the generator 11 driven by the engine, the other brush being grounded.

40 The charging switch 10 which does not form part of the present invention, is of usual construction and has for its purpose to prevent current from flowing back from the battery 2 to the generator 11. Upon starting of the engine by operating the starter switch 4, the generator 11 supplies current to the battery 2 in a well known manner.

45 From the distribution point 12 arranged in the line 9, a line 13 leads to one terminal of the usual horn 14 the other terminal of which is connected through a line 15 with a contact carrier

16 the contact of which cooperates with a movable contact carried by a spring 17. An electromagnet 19 provided with a coil 18 cooperates with an armature 20 carried by the spring 17 in such a manner that the contacts of the contact carriers 16 and 17 are closed, if the coil 18 is not passed by a current, but opened, if the electromagnet 19 is energized and attracts the armature 20. A line 21 connects one end of the coil 18 with the generator 11, and the other end to the ground 1.

The contact spring 17 is connected by a line 22 through a door switch 23 with the ground 1. This switch 23 of conventional form is arranged at one of the doors of the vehicle and is opened by any desired, well known device (not shown), if the door is properly closed, but closed, if the door is being opened. To each of the doors, one similar switch is associated and all these door switches are arranged in parallel. In the present example, besides the door switch 23 a second door switch 24 is shown, but it will be seen that any desired number of such switches may be provided according to the number of doors.

The upper terminal of the horn 14 is connected by a line 25 through a hand-operated switch 26 to the ground 1. This commonly used switch serves to operate the horn 14 intentionally in a well-known manner. From the point 27 of the line 15, there extends a line 28 through a hand-operated switch 29 to the point 30 of the line 22 so that the switch 29 is arranged in parallel with the electromagnetic switch 16 to 20. Moreover, from the line 22 leads a line 31 through the pair of contacts 8 to the ground 1.

From the distributing point 12 leads the primary ignition circuit 32 to the primary winding 33 of the inductive or ignition coil and further through the contact breaker lever 35 actuated by the rotating cam 34, and the breaker contacts 36 to the ground 1. A condenser 37 is arranged in parallel with these contacts in a well known manner. The secondary winding 38 of the ignition coil is connected through a line 39 to the distributor 40 which supplies the spark plugs 41 with current. From the line 32 leads a line 42 to an additional winding 43 of the ignition coil, which winding extends oppositely to the primary winding 33, and further through the contacts 8 to the ground 1.

Contacts 44 controlled by the starter switch 4 are connected through a line 45 to the distributing point 12. Parallel with these contacts 44, there is arranged a switch 47 by means of a line 46, which switch is held in its open position by a spring, and is closed by depressing the clutch pedal or lever 48.

From the distributing point 12, moreover, extend further lines (not shown) which supply current to the several current consuming devices, such as screen-heater, screen-wiper, indicator or the like.

The system operates as follows: With the engine standing still, the alarm circuit extends from the distributing point 12 through line 13, horn 14, line 15, contact carrier 16, contact spring 17 and further through line 22, door switch 23 (or 24) to the ground 1. If the ignition switch 6 is closed and the contacts 7 thus interconnected, the distributing point 12 is supplied with current from the battery 2. If, moreover, one of the doors of the vehicle is open and therefore one of the door switches 23, 24 . . . closed the horn 14 is operated.

When the ignition switch 6 is open, that is,

5 the contacts 7 broken and an unauthorized person attempts to connect the primary ignition circuit 32 directly to the battery 2 in any desired manner, for instance by means of a length of wire, when, moreover, one of the doors is open, the horn 14 is actuated since the distributing point 12 is supplied with current and therefore the said alarm circuit completed. The same effect is obtained, when, with the engine standing still, the driver opens a door to leave the vehicle, and has forgotten to switch off the ignition switch 6.

When the engine has been started, but the generator 11 has not yet reached a sufficient number of revolutions to cause the electromagnet 19 to attract the armature 20, the horn 14 does not sound, if all doors are properly closed. If, however, one of the doors is open and therefore one of the door switches 23, 24 etc. closed, the alarm circuit is completed thereby so that the horn 14 indicates to the driver that the door or doors are open.

It is, moreover, desirable to indicate to the driver during the drive, whether all doors are closed. For this purpose, the driver temporarily closes the control switch 29 whereby the broken contacts of the electromagnet 19 are bridged over and the horn indicates to the driver that one or more of the doors are not properly closed, without the necessity for the driver to turn back during the drive.

If the ignition switch 6 is switched off and therefore the contacts 8 interconnected, but the ignition circuit 32 has been directly connected to the battery 2 by an unauthorized person and the attempt is made to start the engine by operating the starter switch 4, the horn 14 sounds also with the doors closed, since in such a case the contact spring 17 is connected through the line 31 and the contacts 8 to the ground 1. At the same time, current flows through line 42, additional winding 43 and contacts 8 to the ground 1 so that the inductive effect of the primary winding 33 is weakened and sparks are not obtained at the spark plugs 41. It will be seen, therefore, that the engine cannot be started in spite of repeated attempts.

When the driver actuates the starter switch 4, but has forgotten to previously switch on the igniting switch 6, current flows from the battery 2 through the starter switch 4, line 45, distributing point 12, line 13, horn 14, line 15, contacts of the contact carriers 16 and 17, lines 22 and 31, contacts 8 to the ground 1 so that the alarm signal indicates to the driver that the ignition switch 6 is open. The same effect is obtained, when an unauthorized person has connected the ignition circuit 32 to the battery and tries to start the engine.

When an attempt is made to depress the clutch pedal 48 with the engine standing still, in order to separate the engine from the gear set, the switch 47 is closed and the distributing point 12 therefore supplied with current which flows from this point along the same path as described in the foregoing paragraph. Also in this case the alarm signal sounds, irrespective whether or not the doors are closed.

What I claim is:

70 1. An electrical safety device for motor vehicles driven by an internal combustion engine, which comprises a battery, a generator driven by said engine and connected to said battery, a primary ignition circuit comprising a primary winding of an ignition coil, an alarm circuit

arranged in parallel with said ignition circuit and comprising an alarm device, an electromagnetic switch in said alarm circuit, electromagnetic means connected to said generator and opening said electromagnetic switch, if energized by said generator, at least one door switch in said alarm circuit, said door switch being opened, if a door of the vehicle is closed and vice versa, a hand-operated ignition switch comprising two pairs of contacts, one pair of which is arranged in said ignition circuit and is interconnected by said ignition switch in its closed position, whereas the other pair of contacts is arranged in said alarm circuit in parallel with said door switch and is interconnected by said ignition switch in its open position, and an additional winding of said ignition coil, connected to that part of said alarm circuit which is connected to the last named pair of contacts, said additional winding being arranged so that its inductive effect is opposite to that of the primary winding of said ignition coil.

2. An electrical safety device for motor vehicles driven by an internal combustion engine, which comprises a battery, a generator driven by said engine and connected to said battery, a primary ignition circuit, an alarm circuit arranged in parallel with said ignition circuit and comprising an alarm device, an electromagnetic switch in said alarm circuit, electromagnetic means connected to said generator and opening said electromagnetic switch, if energized by said generator, at least one door switch in said alarm circuit, said door switch being closed if the associated door is being opened so as to complete said alarm circuit with the engine standing still and therefore said electromagnetic switch being closed, and a hand-operated ignition switch comprising two pairs of contacts, one pair of which

is arranged in said ignition circuit and is interconnected by said ignition switch in its closed position so as to complete said ignition circuit, as well as at the same time said alarm circuit, if said electromagnetic switch and said door switch are closed, whereas the other pair of contacts is arranged in said alarm circuit in parallel with said door switch and is interconnected by said ignition switch in its open position.

5 10 3. An electrical safety device for motor vehicles driven by an internal combustion engine as claimed in claim 2, wherein a starter switch is arranged in parallel with said ignition switch so that, if said ignition switch is opened and said 15 starter switch closed, said alarm circuit is completed and said alarm device actuated.

10 15 4. An electrical safety device for motor vehicles driven by an internal combustion engine as claimed in claim 2, wherein a hand-operated 20 control switch is connected to said alarm circuit and arranged in parallel with said electromagnetic switch so that, when said control switch and said door switch are closed, said alarm circuit is completed and said alarm device actuated.
